Primary Examiner — Katie Jane Stofko(74) *Attorney, Agent, or Firm* — Ladas & Parry LLP(57) **CLAIM**

The ornamental design for a food item, as shown and described.

DESCRIPTION

FIG. 1 is a perspective view of a food item showing the new design;

FIG. 2 is a side elevation view thereof;

FIG. 3 is a top plan view thereof; and,

FIG. 4 is a bottom plan view thereof.

The broken lines in FIG. 1 show environment that forms no part of the claimed design, while the broken lines in FIG. 3 illustrate portions of the food item that form no part of the claimed design. The food item is radially symmetrical about its central vertical axis. Thus only one elevation view is shown.
